UNITED STATES PATENT OFFICE.

MICHAEL J. CONNERTON, OF DANVILLE, KENTUCKY.

SWITCH-CHAIR.

1,104,629.

Specification of Letters Patent. Patented July 21, 1914.

Application filed November 4, 1913. Serial No. 799,172.

To all whom it may concern:

Be it known that I, MICHAEL J. CONNERTON, a citizen of the United States, residing at Danville, in the county of Boyle and State 5 of Kentucky, have invented new and useful Improvements in Switch-Chairs, of which the following is a specification.

This invention is an improved joint and filler block for use in a standard railroad 10 switch to effect a solid connection between the heel of the switch and the stock rail, at the joint where the switch point is connected to the main track rail or lead rail, to hold the track at the heel of the switch to 15 the proper gage and prevent spreading and also prevent the rail from cutting into the ties, the invention consisting in the construction, combination and arrangement of devices hereinafter described and claimed.

20 In the accompanying drawings: Figure 1 is a plan of the heel portion of a standard railroad switch provided with a joint and filler block constructed in accordance with my invention. Fig. 2 is a side elevation of 25 the same. Fig. 3 is a vertical transverse sectional view of the same on the plane indicated by the line *a—a* of Fig. 1. Fig. 4 is a similar view of the same on the plane indicated by the line *b—b* of Fig. 1.

30 For the purposes of this specification, I show a main track or lead rail at 1 and a stock or switch rail at 2. In accordance with my invention, I provide a supporting plate 3 which is arranged under the said rails at 35 the joint, and is provided with a longitudinal wedge-shaped wall 4 on its upper side, which separates and abuts against the opposing base flanges 5—6 of the said rails. This wall is wedge-shaped longitudinally, 40 its sides converging in one direction, as shown in Fig. 1, and indicated in Figs. 3 and 4, and the base plate 3 is also correspondingly shaped and is narrower at one end than at the other. The plate is also 45 provided with web walls 7—8 which converge in one direction and bear respectively against the opposing webs of the rails 1—2 and are provided with base portions 9—10, respectively, which overhang and bear on 50 the upper sides of the inner base flanges of the rails and are formed integrally with and connect the said web walls to the said wall

4, the plate, with its wall 4, web walls 7—8 and base portions 9—10 being integral and being preferably rolled. The plate 3 bears 55 on the upper sides of the cross ties and is secured thereto by means of suitable spikes and serves to prevent the rails from cutting into the ties.

On the outer sides of the rails are fish 60 plates 11 which are of the usual construction and which are secured to the web walls of the joint and filler block, and are also secured to the respective rails by means of suitable bolts, such as indicated at 12 in 65 Figs. 3 and 4.

It will be understood that my improved joint and filler block effects a solid connection between the heel of the switch and the stock rail, at the joint where the switch 70 point is connected to the main track rail or lead rail, serves to hold the track at the heel of the switch to the proper gage and prevents spreading of the rails in addition to preventing the rails from cutting into the 75 ties.

I claim:

1. As an article of manufacture a joint and filler block comprising a supporting plate for arrangement under the rails of a 80 railway switch at the joint and provided on its upper side at its center with an integral longitudinal wedge shaped wall to separate and abut against the opposing base flanges of the rails and also provided with integral 85 web walls converging in the same direction as the sides of the first-named wall, said web walls serving to bear against the opposing webs of the rails and having base portions to overhang the inner base flanges of 90 the rails, the side portions of said plate being unobstructed and extending outwardly in opposite directions from said wedge shaped wall.

2. In combination with the lead and stock 95 rails of a railway switch, a joint and filler block comprising a supporting plate arranged under said rails at the joint and provided with an integral longitudinal wedge shaped wall on its upper side separating and abutting against the opposing base flanges of the rails and also provided with integral 100 web walls converging in one direction, bearing against the opposing webs of said rails

and having base portions overhanging the inner base flanges of the rails and connecting the said web walls to the first-named walls, the side portions of said plate being 5 unobstructed and extending outwardly beyond the outer sides of the said rails, fish plates on the outer sides of said rails and bolts connecting the web walls of the joint

and filler blocks, the rails and fish plates together.

In testimony whereof I affix my signature in presence of two witnesses.

MICHAEL J. CONNERTON.
